COMBINED BUMPER, FRONT PANEL, GRILLE AND HEADLIGHT ASSEMBLY

Henry G. Haga, Bloomfield Hills, and Jerry P. Palmer,
Royal Oak, Mich., assignors to General Motors Corporation,
Detroit, Mich.

Filed Feb. 22, 1974, Ser. No. 444,865

Term of patent 3½ years

Int. Cl. D12—08

U.S. Cl. D12—170

FIG. 1 is a side elevational view of a combined bumper, front panel, grille and headlight assembly showing our new design;

FIG. 2 is a top plan view thereof;

FIG. 3 is a front elevational view thereof; and

FIG. 4 is a perspective view thereof.

The broken lines in the drawings are for illustrative purposes only.

We claim:

The ornamental design for a combined bumper, front panel, grille and headlight assembly, substantially as shown and described.
